UNITED STATES PATENT OFFICE

ALEX HAJDU, OF HOOVERVILLE, PENNSYLVANIA

TOY

Application filed December 31, 1930. Serial No. 505,850.

This invention relates to certain new and useful improvements in toys.

The primary object of the invention is to provide a toy of the spinner or whirligig type that may also be used as a hand operated fan and has particular reference to a wire frame structure for rotatably supporting a reel block carrying a spinner blade.

With the above and other objects in view that will become apparent as the nature of the invention is better understood, the same consists in the novel form, combination and arrangement of parts hereinafter more fully described, shown in the accompanying drawing and claimed.

In the accompanying drawing to which reference is had by like characters designating corresponding parts throughout the several views:—

26 Figure 1 is a top end elevational view of a toy spinner constructed in accordance with the present invention;

Figure 2 is a side elevational view of a toy spinner showing a single wire strand bent into the form of a supporting frame for rotatably supporting a reel block or spool with a loop at one side of the frame constituting a guide for the operating cord;

Figure 3 is another side elevational view;

Figure 4 is a cross-sectional view taken on line 4—4 of Figure 2 showing the guide loop at the side of the spool supporting frame for the operating cord; and

Figure 5 is a longitudinal sectional view taken on line 5—5 of Figure 2 showing the bearing screw pins carried by the reel block or spool forming journals for the spool in the wire frame.

Referring more in detail to the accompanying drawing, there is illustrated a spinner toy comprising a reel block or spool carrying a spinner blade and a single wire strand bent to provide a supporting frame for the spool. The spool 10 is circumferentially dished or concaved to cause the operating cord wound thereon to be located substantially midway the ends thereof, the cord being guided by a part of the wire frame. Screw pins 11 and 12 are threaded into opposite ends of the winding spool 10 with unthreaded portions of

the shanks of the screw pins projecting outwardly of the ends of the spool to facilitate mounting of the spool in the wire frame.

The wire frame is formed from a single strand of wire or like material and is of U-shape having a side 13 bent intermediate its ends to provide an eye or guide 14 for the operating cord. The outer end of the side 13 of the frame is bent at right angles as at 15 with the terminal end thereof bent to form an eye 16 through which the screw pin 11 freely extends. A spinner blade 17 is secured intermediate its ends to the screw pin 11 and is rotatable with the screw pin and spool 10.

The inner end of the frame side 13 is bent at right angles as at 17' in the same direction as the outer bent end 15, the section 7 being further bent to provide an eye 18 through which the screw pin 12 extends as illustrated, the frame wire from the bent or eye portion 18 being directed inwardly at right angles to the bent end 17 as at 19 for attachment to a handle 20.

An operating cord 21 is wound upon the spool 10 with the inner end thereof anchored to the spool, the free end of the operating cord 21 being threaded through the eye 14 and carrying at its end outwardly of the eye 14, a gripping device such as a ball 22 of greater diameter than the eye 14 to maintain the cord 21 and ball 22 in operative position.

It will be observed from several of the figures that the bearing eyes 16 and 18 for the screw pins 11 and 12 are spaced a distance apart greater than the length of the spool 10 so that in the operation of the device, the operating cord in being wound and unwound from the spool will assume a position centrally of the spool by said cord passing through the guide eye 14, the spool having a tendency to rise and fall in the guide frame when tension is placed upon the operating cord and preventing the operating cord from becoming entangled with the ends of the spool and the screw pins. It will also be observed that a single wire strand is employed for the support of the spool and for attachment to a handle, one end of the wire strand being bent to form an eye, a U-shaped frame with an intermediate guide eye for

the operating cord and another guide eye for rotatably supporting the other end of the spool. It will be understood that in the operation of the device a pull on the ball 22 will effect rotation of the spool 10 and spinner blade 17 carried thereby in one direction and when the operating cord has been completely unwound from the spool, continued rotation of the spool in the same direction will effect rewinding of the cord on the spool and properly position the ball 22 relative to the wire frame for the subsequent operation.

While there is herein shown and described the preferred embodiment of the invention, it is nevertheless to be understood that minor changes may be made therein without departing from the spirit and scope of the invention as claimed.

Having thus described the invention, what is claimed is:—

20 A spinner toy of the character described, comprising a frame formed of a single strand of wire having a straight shank, a handle in which said shank is embedded, the wire strand outwardly of the straight shank being bent into U-shape to form a spool holder with a coiled eye at each end of the holder in line with the shank and a coiled eye in the closed side of the U-shaped holder, a spool arranged in axial alignment with the end eyes, a spinner element, and screw pegs passing through the end eyes and fastened in the ends of the spool and forming pivots for the same, one of said screw pegs being connected to the spinner element.

In testimony whereof I affix my signature.
